CLAIM

I claim the ornamental design for an electrical connector, as shown.

DESCRIPTION

FIG. 1 is a front elevational view of an electrical connector of my new, original and ornamental design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front, bottom, left side perspective view thereof;

FIG. 8 is a back, bottom, left side perspective view thereof; and,

FIG. 9 is a back, top, left side perspective view thereof.
